PHOTOGRAPH MOUNT

Jan Irvin Parson, Santa Ana, Calif.
(460 Abbie Way, Costa Mesa, Calif. 94527)

Filed June 13, 1974, Ser. No. 478,865

Term of patent 7 years

Int. Cl. D16—99

U.S. CL. D61—1 S

FIG. 2

FIG. 1

FIG. 5

FIG. 7

FIG. 3

FIG. 6

FIG. 4

FIG. 1 is a front perspective view of a photograph mount showing my new design;

FIG. 2 is a rear perspective view thereof;

FIG. 3 is a rear elevational view thereof;

FIG. 4 is a front elevational view thereof;

FIG. 5 is a top plan view thereof;

FIG. 6 is a cross-sectional view thereof as taken from line 6—6 of FIG. 3; and

FIG. 7 is a left side elevational view thereof.

I claim:

The ornamental design for a photograph mount, substantially as shown and described.
